UNITED STATES PATENT OFFICE.

GEORGE T. LEWIS, OF PHILADELPHIA, PENNSYLVANIA.

IMPROVEMENT IN THE MANUFACTURE OF ZINC.

Specification forming part of Letters Patent No. 38,493, dated May 12, 1863.

To all whom it may concern:

Be it known that I, GEORGE T. LEWIS, of the city of Philadelphia, in the county of Philadelphia and State of Pennsylvania, have invented a new and useful improvement in the manufacture of metallic zinc or spelter from the pure or impure oxide of zinc, the blue powder of zinc, or any compound of zinc obtained by volatilization; and I do hereby declare that the following is a full, clear, and exact description of the same.

My invention consists in submitting the oxide or other compound of zinc, either alone or mixed with the coal or other carbonaceous matter used as fuel for charging the muffles or retorts in which the reduction to the metallic condition is effected, to pressure or pressure and friction combined, whereby I bring the material to a condition in which it is better adapted for the charging of the muffles or retorts—that is to say, I give it increased compactness and gravity, which enables the muffles or retorts to be charged with a much greater quantity than when the material has not been so treated, thereby not only saving time in the process, but wear and tear and the breakages of the muffles or retorts, which often occur by cooling when charging, such breakage being a serious loss, as the muffles or retorts are expensive.

The pressure or pressure and friction combined may be applied to the material by any

convenient and suitable means. Pressure alone may be applied by means of any suitable press; but I prefer to subject the material to pressure and friction at the same time, and for this purpose I generally submit it to the action of edgerunners or chassers—such as are employed for the crushing of linseed preparatory to the expression of the oil therefrom—which are the means I have found best adapted for the purpose, the pressure being produced by the weight of the runners or chassers rolling over the material and the friction by their revolution around the upright shaft, to which they are attached.

I do not confine myself to any particular means or mode of applying the pressure and friction; but

What I claim as my improvement in the manufacture of metallic zinc or spelter from the oxide or blue powder of zinc or from any compound of zinc obtained by volatilization, and desire to secure by Letters Patent, is—

Subjecting the oxide or other compound of zinc, either alone or mixed with the coal or other fuel, to pressure or pressure and friction before charging it into the muffles or retorts, substantially as and for the purpose herein specified.

GEORGE T. LEWIS.
